ARTICLE PICK-UP DEVICE

Richard M. Cringle, Corning, Calif.

Application July 8, 1936, Serial No. 89,635

1 Claim. (Cl. 294—104)

This invention relates to new and useful article pick-up devices, and although more particularly adapted for picking up eggs from a nest, the device may be used for picking up various other articles.

Among the several objects of the invention are to provide a pick-up device which is extremely easy to operate, and to provide a device which is composed of few parts and is therefore simple

10 in construction and is cheap to manufacture.

With the above and other objects in view which will more fully appear, the nature of the invention will be more clearly understood by following the description, the appended claims, and the 15 several views illustrated in the accompanying drawing.

In the drawing:

Figure 1 is a top plan view of a pick-up device constructed in accordance with my invention,

20 Figure 2 is a side elevation thereof,

Figure 3 is a perspective view of the stationary jaw, and

Figure 4 is a perspective view of the movable jaw.

25 Like reference numerals designate corresponding parts throughout the several figures of the drawing.

Referring to the drawing, my invention comprises four main parts, a handle A, a fixed upper jaw B, a movable lower jaw C, and a manually operable means D for the movable jaw.

The handle A is preferably formed of wood and is preferably rectangular in cross section to form a bottom face 5, side faces 6, 6, and a top face 7.

30 The fixed upper jaw B is formed of a single length of wire which is bent intermediate its ends to form a resultant elongated loop 8, and a shank 9.

The shank 9 is formed by first bending the end portions 10, 10 of the wire inwardly as at 11, 35 and then positioning the end portions side by side and finally bending the extreme ends of the wire to form downwardly extending prongs 12,

12. The loop-shaped jaw B projects longitudinally beyond the end of the handle, and the 40 shank 9 is positioned upon the top face 7 of the handle, with the prongs projected into the handle.

In order to further secure the fixed jaw B against movement relative to the handle, I have provided upper and lower clamping plates 13 and 14 which 45

50 are provided with upwardly and downwardly extending flanges 15 and 16 respectively for engaging the side faces 6, 6 of the handle. A rivet 17

passes through the clamping plates, between the end portions 10, 10 of the shank 9, and through 55 the handle A.

The movable lower jaw C is formed from a single length of wire which is bent intermediate its ends to form a resultant elongated loop 18, and a lever 19. The movable jaw C is positioned below and in spaced relation to the fixed jaw B, and normally the jaws are spaced and in parallelism. The lever 19 is formed by the end portions 20, 20 of the wire, and consequently these portions form lever arms. These lever arms are positioned against the side faces 6, 6 of the handle 10 and are formed with upwardly projecting bearing eyes 21, 21, which receive a bearing pin 22 extending transversely through the handle and terminates in eyes for retaining the lever arms 15 against displacement. The lever arms extend 15 upwardly at an inclination to a point above the top face 7 of the handle, and their extreme ends are twisted together as at 23 to form a resultant eye 24 which cooperates with said top face 7 to limit the closing movement of the movable jaw 20 C.

The operating means D for the movable jaw C comprises a thrust rod 25 which is slidably mounted on the upper face 7 of the handle between spaced guide eyes 26, 27 secured to the handle. The inner end of the rod is provided with an eye 28 having pivotal connection with the eye 24 of the movable jaw lever 19, and the outer end of the rod is provided with an upstanding operating eye 29 for engagement by the hand of the operator. A coil spring 30 is positioned between the eye 29 and the guide eye 27 to yieldably retain the movable lower jaw C in its normal position in spaced parallel relation with the upper jaw B.

35 In operation, the movable jaw C is opened by the operator pushing the thrust rod 25 forwardly against the tension of the spring 30, and after the egg or other article has been positioned between the jaws, the thrust rod is released and the spring 30 will close the movable jaw and thereby 40 yieldably clamp the egg or other article between the jaws. In order for the operator to release the egg or other article, it is only necessary to open the movable jaw C by pushing the thrust 45 rod 25.

It is of course to be understood that the details of structure and arrangement of parts may be variously changed and modified without departing from the spirit and scope of my invention.

50 I claim:

In an article pick up, the combination with a handle of rectangular cross section; of a fixed jaw secured to one end of the handle and formed of a single length of wire bent intermediate its 55

ends to form an elongated loop projecting beyond the end of the handle, and in longitudinal alignment therewith, the end portions of the wire forming a shank extending longitudinally along the upper face of the handle and having their extreme ends bent downwardly to form anchoring prongs engageable in the handle, a clamping plate disposed above the shank and having de-

pendent flanges engaging the sides of the handle, and a rivet passing through the clamping plate and between the end portions of the wire and through the handle; a movable jaw pivoted on the handle for cooperation with the fixed jaw; and manually operable means mounted on the handle for actuating the movable jaw.

RICHARD M. CRINGLE.
